WILLIAM RHODES ARNOLD, OF PROVIDENCE, RHODE ISLAND.

Letters Patent No. 65,859, dated June 18, 1867.

IMPROVEMENT IN LAPPING BRAID.

The Schedule referred to in these Letters Patent and making part of the same.

TO ALL WHOM IT MAY CONCERN:

Be it known that I, WILLIAM RHODES ARNOLD, of Providence, in the county of Providence, and State of Rhode Island, have invented a new and improved Machine for Measuring and Lapping Tape and Braid; and I do hereby declare that the following is a full, clear, and exact description thereof, which will enable others skilled in the art to make and use the same, reference being had to the accompanying drawings, forming part of this specification, in which—

Figure 1 is a perspective view of my invention.

Figure 2 is a detached front view of the main driving-wheel.

Figure 3 is a central cross-section taken on the line $x x$, fig. 2.

Figure 4 is a detached view of a guide-pin.

Similar letters of reference indicate like parts.

The object of this invention is to measure tape, braid, binding, or other similar goods, into exact lengths for the trade, say in pieces five yards long, and at the same time form them into "sticks" by lapping or folding. Upon a solid base, A, are secured two standards B B', upon and between which is hung a plate spur-wheel C, to be turned by hand with the crank D. The spur-wheel C gears into a pinion, E, above on a sliding-shaft, a , which has its bearings in the standards B B'. Just within the periphery of the gear-wheel C, on the side of it, is placed a cam, b , which extends around nearly or quite one-half of the circumference of the wheel, as shown in fig. 2. The face of the cam b is in the plane of the side of the plate-wheel C, and projects above the plate-face one-half inch, as shown in fig. 3. One end of the cam is bevelled, and the other end has a nose or projection, b' , to form a recess behind it. On the inside of the standard B', at the lower part, is fastened one end of a spring, c , which extends up and terminates in a fork, c' , which clutches or clasps the shaft a between the ring-shoulders $d d$ that confine its movement on the shaft. A pin, g , having a hooked outer end, h , is fastened on the spring c , so that the ends of the pin may strike the flat plate-face of the wheel C, and the hook h lie in the recess behind the projection b' on the cam b . The shaft a may be moved in its bearings lengthwise, so as to press the upper end of the spring c outward, and raise the pin g so that the hooked end h will lie upon the cam b , when necessary, as hereinafter described. On the end of the sliding-shaft a , outside of the standard B', is affixed a pair of lapping-bars, $i i$, which for ordinary use are made about seven inches apart, and as the gear-wheel C is made proportioned to the pinion E, so as to give the shaft a fourteen turns in one revolution, a "stick" of five yards of braid is formed on the lapping-bars $i i$ for each revolution of the gear-wheel C.

When the machine is started, an end of the braid having been caught on a hook, h , on one of the lapping-bars i , the shaft a is pushed forward so that the end of the pin g is mounted on the cam b at the projecting end b' . The gear-wheel C is then turned until the pin g slips off the cam at the opposite inclined end, when it continues to travel around on the face of the plate of the wheel C until the hook h passes into the recess behind the projection b' , and thus stops the machine. It will be observed that during this revolution of the gear-wheel C, the turning of the lapping-bars $i i$ has folded or lapped around them a piece of braid or tape of a definite length, fed from a suitable frame, as shown in red, and the length of braid thus folded or lapped has been formed in two parts, folds, or laps, by the action of the spring c , which has forced the shaft a backward in its bearings the thickness of the cam b on which the guide-pin g travelled when the pin slipped from the cam. One of the laps or parts of the length of braid thus folded was made over one point or part of the lapping-bars $i i$, while the pin g moved on the cam b , and the other part while it moved the balance of the revolution of the gear-wheel C over its plate-face. The length is then made into what is known to the trade technically as a "stick" of braid by the operator cutting it off and turning one end under. To start the machine again, the gear-wheel C is turned back just enough to release the hook h of the pin g from the projection b' of the cam b , when the shaft a is pushed forward, so as to raise the end of the pin g upon the cam b , for repeating the operation of lapping and measuring a piece of braid, as before described.

Having thus described my invention, I claim as new, and desire to secure by Letters Patent—

1. The machinery for measuring and lapping braids, tapes, &c., having a shifting and positive stop-motion, substantially as herein described.
2. The sliding-shaft a , the spring c , the pin g , and the cam b on the gear-wheel C, combined and operating substantially as and for the purposes herein described.

WM. RHODES ARNOLD.
